LIGHTING DEVICE

Application filed March 30, 1931. Serial No. 526,361.

This invention relates to lighting devices of the sparking type heretofore employed in igniting gas and other combustibles and more specifically to an improved lighting device of this type which is designed so as to more efficiently perform its function than did similar devices heretofore known, the predominant object of the invention being to provide an improved lighting device of the type referred to which is provided with a plurality of sparking elements adjustable successively into operative position relative to an abrasive member whereby the period of time during which the device may be used before it is necessary to renew the spark producing means thereof is very greatly increased.

Lighting devices of the type disclosed herein are used extensively in igniting the gases issuing from gas-burning cutting and welding torches, and considerable annoyance was caused by the fact that the devices heretofore employed for this purpose each included a single sparking element which very quickly was consumed by repeated operation of the lighting device and hence had to be frequently renewed. To eliminate this annoyance we have devised the improved lighting device disclosed herein which, briefly stated, includes a plurality of sparking elements which are adjustable successively into operative position relative to the abrasive member of the device. The operation of adjusting a new sparking element into operative position after a previously operative sparking element has been consumed is an extremely simple one, hence, the device may be maintained in operative condition with a minimum effort for a much greater length of time than was possible in the use of the lighting devices heretofore employed.

Another feature of the invention resides in the fact that the sparing elements of our improved device are coated with a preparation which prevents rapid decomposition of said

elements. This feature is important inasmuch as these elements are highly susceptible of rapid decomposition prior to being placed in use because of contact of air therewith and by coating the elements as described the effective life of said elements is very substantially prolonged.

Fig. 1 is an elevation of the improved device.

Fig. 2 is an enlarged section on line 2—2 of Fig. 1.

Fig. 3 is a section on line 3—3 of Fig. 2.

Fig. 4 is a section on line 4—4 of Fig. 1.

Fig. 5 is an elevation of a modified form of a sparking element of the device.

Fig. 6 is a cross section of one of the sparking elements showing the coating thereon.

In the drawings, wherein is shown for the purpose of illustration, merely, one embodiment of the device and two embodiments of the sparking elements thereof, A designates the device generally, said device including a handle portion 1, an abrasive member 2 which is supported by a portion of said handle 1, and a plurality of sparking elements, or flints, 3 supported by another portion of the handle 1 in a manner to permit of one of said sparking elements being moved with respect to and in contact with said abrasive member so as to produce sparks. The handle 1 preferably is formed from a strip of metal, or other suitable material, which is possessed of considerable resiliency, said strip of material being bent to assume a substantially U shaped form as shown in Fig. 1 and with a bowed connecting portion 1^a at the outer end of the handle. For the purpose of convenience in describing the invention we designate one leg portion of the handle by the reference character 1^b and the other leg portion thereof by the reference character 1^c.

The end portion of the leg portion 1^b of the handle 1 opposite the end thereof which joins the bowed connecting portion 1^a is shaped as clearly illustrated in Fig. 1 of the

drawings; that is to say a yoke 4 is provided which is comprised of oppositely disposed side walls 4^a and 4^b and a top or end wall 4^c which is formed integral with said side walls 4^a and 4^b. The yoke 4, in the embodiment of the invention illustrated in the drawings is integrally joined to the leg portion 1^b of the handle 1 by an inclined connecting portion 5 whereby the handle 1 and the yoke 4 10 provide a unitary structure. Also the side wall 4^b of the yoke is elongated as indicated at 6 in Fig. 1 for a purpose to be hereinafter set forth.

Supported within the yoke 4 is a box-like structure 7 which houses the abrasive member 2 of the device, said box-like structure comprising oppositely disposed end walls 7^a, top and bottom walls 7^b and 7^c respectively, and a back wall 7^d. The walls referred to 15 produce an integral structure which is open at the front as shown clearly in Fig. 2, the top wall 7^b of this structure preferably being of less width than the bottom wall 7^c and being in contact with the inner face of the wall 4^c of the yoke 4. The abrasive member 2, which may be formed of any suitable material such as metal or the material known commercially as "Lava", is provided with an opening 2' which extends longitudinally 20 therethrough from end to end thereof, and the end walls 7^a of the box-like structure 7 are provided with openings 8 which are alined with said opening 2'. In like manner the side walls 4^a and 4^b of the yoke structure 25 are provided with openings 9 formed therethrough which are alined with the opening 2' formed through the abrasive member and the openings 8 formed in the end walls of the box-like structure 7. Extended through the 30 alined openings 2', 8, and 9 in the abrasive member 2, yoke 4, and the box-like structure 7 is a bolt 10 which is provided with a head portion 10^a at one end, and a screwthreaded portion at the opposite end which receives a 35 nut 11. The nut 11 is screwed inwardly on the screwthreaded end portion of the bolt 10 so as to cause said nut and the head portion of the bolt to firmly contact with the side walls 4^a and 4^b whereby the yoke 4 and box-like structure 7 are securely fixed together 40 and the abrasive member is maintained in its proper position.

The end portion 12 of the leg portion 1^c of the handle 1 is twisted with respect to the 45 remainder of said leg portion until the width of said portion 12 is disposed in a vertical plane which is approximately parallel with respect to the axis of the abrasive member 2. Also this portion 12 is provided with an extension 12' at its upper end which is shaped as shown in Fig. 1. The portion 12 is also provided with an opening 13 through which a screwthreaded bolt 14 is extended, the head portion 14' of said bolt being in contact with 50 the outer face of the portion 12 and being

permanently secured to said face by solder or other means 14^a.

Rotatably supported by the bolt 14 in contact with the inner face of the portion 12 of the leg portion 1^c is a head 15 which is provided with a plurality of radial arms 16. Also said head, at points intermediate the arms 16 is provided in an edge portion thereof with a plurality of notches 17. The portion 12 of the leg portion 1^c is provided with a pin 18 which extends inwardly from the inner face of said portion 12, said pin being provided with a reduced portion 19 which is disposed in an aperture formed through the portion 12 and is riveted in place therein whereby said pin is securely fixed in place. As shown very clearly in Figs. 1 and 3 the lowermost notch 17 of the head 15 embraces the pin 18 in a manner to prevent unintended rotation of the head 15 about the bolt 10. At the outer end of the radial arms 16 of the head 15, we arrange the sparking elements 3 of the device, there being one sparking element supported by each arm and said sparking elements are fixed in place in any suitable manner, as, for instance, by having end portions thereof driven into apertures 20 formed through the arms.

Mounted on the screwthreaded end portion of the bolt 14 is a nut 21 which is provided with an elongated sleeve 21'. The inner end of the sleeve 21' of the nut referred to may be screwed into close contact with the head 15 so as to force said head into firm contact with the inner face of the portion 12 of the leg portion 1^c of the handle 1. It will be noted by referring to Fig. 1 of the drawings that the downwardly extended portion 6 of the side wall 4^b of the yoke 4 serves as a stop with which the sleeve 21' of the nut 21 may contact to prevent undue outward movement of the portion of the leg portion 1^c which supports the sparking elements. Also as shown in Fig. 2 the head portion of the nut 21 overlaps the box-like structure 7 whereby the end of the leg portion 1^c which supports the sparking elements is prevented by contact of said head portion of the bolt with the rear wall of said box-like structure, from springing in a direction away from the abrasive member 2.

The portions 22 of the handle which are gripped when the device is being operated are preferably curved slightly in a transverse direction as indicated in Fig. 4. Also these portions 22 are disposed at such angles that when pressure is applied, in a manner to be hereinafter described, to cause the effective sparking element 3 to move longitudinally in contact with the abrasive member 2, such pressure, because same exerts a force at a right angle to the planes of portions 22 will cause the effective sparking element to be forced firmly against the face of the abrasive member. In order to aid the natural

resiliency of the handle, we may, if desired, provide the device with a spring such as that designated by the reference character 23.

In the operation of the device the uppermost sparking element 3, which is the effective sparking device and which is arranged at all times with its outer end in close contact with the face of the abrasive member 2, is moved longitudinally of the abrasive member in close contact therewith with the result that sparks are produced. Such movement of the effective sparking element is produced by grasping the handle of the device in the hand and quickly moving the leg portions 1^b and 1^c toward each other. After this operation has been performed repeatedly it will be found that the effective sparking element has been practically consumed, and heretofore it was necessary to obtain a new sparking element and perform the time consuming task of removing the stub of the old sparking element and replacing same with a new sparking element. In the use of our improved device, however, it is necessary to merely unscrew the nut 21 to permit the lowermost notch 17 to be freed from the pin 18 by moving the head 15 longitudinally of the bolt 14. The head 15 may then be rotated to bring a new sparking element into effective position adjacent to the abrasive member 2 at which time another notch 17 will embrace the pin 18. The nut 21 may then be screwed inwardly on the bolt 14, whereby the inner end of the sleeve 21' of said nut will force the head 15 against the inner face of the portion 12 of the leg portion 1^c in a manner to prevent disengagement of the lowermost notch 17 from the pin 18 resulting in securely fixing the head 15 in place.

The abrasive member 2 is preferably round in cross-section and is capable of rotation on the bolt 10 and in order to induce such rotation we may provide the abrasive member with a spiral groove 24. The effect of the presence of this spiral groove is that the effective sparking element will contact with the walls thereof when said effective sparking element is moved longitudinally of the abrasive member in a manner to subject the abrasive member to slight rotation. Thus different portions of the face of the abrasive member are positioned for contact with the effective sparking element. Furthermore when effective sparking element contacts with the sharp corners at the walls of the spiral groove the sparking efficiency of the device is very greatly increased.

In Fig. 5 we illustrate an abrasive member which is provided with a plurality of annular grooves 25 spaced longitudinally of the abrasive member. In the use of this form of the device also the sharp corners at the walls of the grooves produce an improved sparking effect.

In order to preserve the sparking elements,

particularly before use thereof in the device, and prevent decomposition thereof caused by the contact of air therewith we prefer to coat said sparking elements with a suitable substance, such, for instance, as lacquer, varnish, or shellac as indicated at 3' in Fig. 6. By so coating the sparking elements the life thereof is very greatly increased and they may be placed in use in the device in such condition that they perform their function with the maximum efficiency.

We claim:

1. A lighting device comprising an abrasive member, a plurality of sparking elements, means for supporting said abrasive member and said sparking elements in a manner to permit movement of said sparking elements relative to said abrasive member, and carrying means for said sparking elements, said carrying means being adjustable relative to said supporting means in a manner to position one or another of said sparking elements in an operative position adjacent to said abrasive member.

2. A lighting device comprising a resilient supporting element of substantially U-shaped formation, an abrasive member supported by a portion of said resilient supporting element, a plurality of sparking elements supported by another portion of said supporting element, said supporting element being yieldable to permit movement of said sparking elements relative to said abrasive member, carrying means for said sparking elements, said carrying means being adjustable in a manner to position one or another of said sparking elements in an operative position adjacent to said abrasive member.

3. A lighting device comprising an abrasive member, a plurality of sparking elements, means for supporting said abrasive member and said sparking elements in a manner to permit movement of said sparking elements relative to said abrasive member, carrying means for said sparking elements, said carrying means being adjustable relative to said supporting means in a manner to position one or another of said sparking elements in an operative position adjacent to said abrasive member, and means for locking said carrying means in positions to which it has been adjusted.

4. A lighting device comprising an abrasive member, a plurality of sparking elements, means for supporting said abrasive member and said sparking elements in a manner to permit movement of said sparking elements relative to said abrasive member, carrying means for said sparking elements, said carrying means being adjustable relative to said supporting means in a manner to position one or another of said sparking elements in an operative position adjacent to said abrasive member, and means for locking said

carrying means in positions to which it has been adjusted, the last mentioned means comprising an element on said supporting means which is engaged by portions of said carrying means in a manner to prevent undesigned movement thereof, and a member adapted to be moved into engagement with said carrying means so as to prevent accidental disengagement of said carrying means and said element.

5. A lighting device comprising an abrasive member, a plurality of sparking elements, means for supporting said abrasive member and said sparking elements in a manner to permit movement of said sparking elements relative to said abrasive member, carrying means for said sparking elements, said carrying means being adjustable relative to said supporting means in a manner to position one or another of said sparking elements in an operative position adjacent to said abrasive member, and means for locking said carrying means in positions to which it has been adjusted, the last mentioned means comprising a pin on said supporting means which is engaged by notches formed in said carrying means in a manner to prevent undesigned movement of said carrying means, a screw-threaded element supported by said supporting means, and a nut screwed on said screw-threaded element and engageable with said carrying means in a manner to prevent accidental disengagement of said notches and said pin.

6. A lighting device comprising an abrasive member, a plurality of sparking elements, means for supporting said abrasive member and said sparking elements in a manner to permit movement of said sparking elements relative to said abrasive member, carrying means for said sparking elements, said carrying means being adjustable relative to said supporting means in a manner to position one or another of said sparking elements in an operative position adjacent to said abrasive member, and means for locking said carrying means in positions to which it has been adjusted, the last mentioned means comprising a pin on said supporting means which is engaged by notches formed in said carrying means in a manner to prevent undesigned movement of said carrying means, a screw-threaded element supported by said supporting means and providing a support for said carrying means, and a nut screwed on said screwthreaded element and engageable with said carrying means in a manner to prevent accidental disengagement of said notches and said pin, said nut being provided with a head portion which overlaps an associated portion of the device in a manner to prevent undue lateral separation of said abrasive member and said sparking elements.

7. A lighting device comprising a resilient supporting element of substantially U-shaped

formation, an abrasive member supported by a portion of said resilient supporting element, a sparking element supported by another portion of said supporting element, said supporting element being yieldable to permit movement of said sparking element relative to said abrasive member, and angularly disposed gripping portions forming parts of said U-shaped supporting element which serve to force the sparking element into close contact with said abrasive member when the device is operated.

8. A lighting device comprising an abrasive member, a sparking element movable relative to said abrasive member, means for supporting said abrasive member and said sparking element, means for rotatably supporting said abrasive member, and a groove formed in the face of said abrasive member which provides sharp corners with which the sparking element contacts in a manner to increase the sparking effect of the device.

9. A lighting device comprising an abrasive member, a sparking element movable relative to said abrasive member, means for supporting said abrasive member and said sparking element, means for rotatably supporting said abrasive member, and a curved groove formed in the face of said abrasive member which serves to impart rotary movement to said abrasive member when engaged by said sparking element and provides sharp corners with which the sparking element contacts in a manner to increase the sparking effect of the device.

In testimony that we claim the foregoing we hereunto affix our signatures.
